UNITED STATES PATENT OFFICE.

WILLIAM A. STEFFEN, OF CRETE, NEBRASKA.

DOOR LATCH.

1,405,350.

Specification of Letters Patent. Patented Jan. 31, 1922.

Application filed September 9, 1920. Serial No. 409,059.

To all whom it may concern:

Be it known that I, WILLIAM A. STEFFEN, a citizen of the United States, residing at Crete, in the county of Saline and State of Nebraska, have invented certain new and useful Improvements in Door Latches; and I do hereby declare the following to be a full, clear, and exact description of the invention, such as will enable others skilled in the art to which it appertains to make and use the same.

The present invention relates to door latches, and aims to provide novel and improved means for latching the double doors of a barn, garage or other building, and constructed and arranged so that both doors can be simultaneously latched and unlatched.

Another object is the provision of swinging latches for the two doors, one of which latches is manually operable, and novel means being provided whereby the movement of the manually-operable latch will move the latch of the other door for simultaneously latching and unlatching both doors.

A further object is the provision of sliding latch bolts for the two doors, one of which is manually-operable, and novel means being provided whereby the other latch is controlled by the manually-operable latch for simultaneously latching and unlatching both doors.

A still further object is the provision of such a latching device which will not only latch both doors in closed position, but which will also support the doors against sagging when in closed position.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawing, wherein:

Fig. 1 is an elevation of the latching device, portions of the doors being broken away, showing the latches in released position.

Fig. 2 is a fragmentary elevation of the swinging latches showing the same in latching position.

The present latching device is intended

for the double doors 4 and 5 of a barn, garage or similar structure, and is preferably used on the inner side of the doors.

In carrying out the invention, there is provided a latch lever 6 fulcrumed, near its upper end, to a bracket 7, secured to the door 4, as at 8, and the upper short arm of the lever 6 comprises one swinging latch, being provided with a terminal hook 9, which is movable into a keeper 10 carried by the door frame. As shown, the lever 6 is arranged near the upper edge of the door 4, with the keeper 10 depending from the lintel of the door frame, and the lower long arm of the lever 6 has a terminal handle 11 for conveniently swinging said lever to engage the hook 9 in and disengage it from the keeper 10.

A second latch lever 12, shorter than the lever 6, is fulcrumed between its ends to a bracket 13, secured, as at 14, to the door 5 near the upper edge thereof, and the upper arm of the lever 12 constitutes a swinging latch, having the terminal hook 15, similar to the hook 9, which is movable into a keeper 16 depending from the lintel of the door frame. The keepers 10 and 16 comprise eye bolts, or the like, and both levers 6 and 12 are swingable in the same direction into and out of engagement with the keepers. A leaf spring 17 is secured to the bracket 13 bears against the lower arm of the lever 12, for disengaging the hook 15 from the keeper 16, when the lever 12 is free to swing.

In order to swing the lever 12 with the lever 6, when the doors are closed, a horizontal push bar 18 is slidable in a guide 19 secured to the door 4 near the vertical edge thereof adjacent to the door 5, and one end thereof is pivotally connected to the lower arm of the lever 6, whereby said bar 18 is slid by the lever 16 when said lever is swung. The bar 18 is movable under the lower end of the lever 12, and has an upstanding lug 20 at its upper edge movable into a notch 21 in the lower end of the lever 12 against a lug 22 of said lever at one side of the notch. Thus, when the keeper 6 is swung to move the hook 9 into the keeper 10, the bar 18 is moved with the lever 6, whereby the lug 20 in engaging in the notch 21 and contacting with the lug 22, will swing the lower arm of the lever 12 in the same direction as the lower arm of the lever 6, thereby moving the hook 15 into the keeper 16, so that both swinging

latches are simultaneously moved to latching position. When the lever 6 is swung to disengage the hook 9 from the keeper 10, the lug 20 and spring 17 will swing the lever 12 to move the hook 15 to releasing position also.

A vertically sliding latch bolt 23 is provided for the lower edge of the door 4, being slideable in guides 24 secured to said door 10 near that edge of the door 4 adjacent to the door 5, and said latch bolt 23 is slid to latching and releasing position simultaneously with the latch hook 9. Thus, a vertical rod 25 has its lower end secured to the latch 15 bolt 23, and is slideable in a guide 26 secured to the door 4, and the upper end of said rod 25 is pivotally connected to one arm of a bell-crank lever 27, having its elbow fulcrumed to the door 4, as at 28, while the 20 other arm of the lever 27 is connected by a link 29 with the lower arm of the lever 6. Thus, when the lever 6 is swung to move the hook 9 into the keeper 10, the lever 27 is swung to depress the rod 25 and move 25 the latch bolt 23 downwardly to latching position.

A vertically slideable latch bolt 30 is also provided for the door 5, adjacent to the latch bolt 23, and is slideable in guides 31 secured to the door 5. The floor or sill underneath the doors has recesses or keepers 32 for the entrance of the bolts, to latch the lower edges of the doors. A coiled wire spring 23 surrounds the bolt 30 and is confined between the lower guide 31 and a shoulder 34 on the bolt 30 whereby to raise the bolt 30 to releasing position when free to do so.

In order to simultaneously move the latch 40 30 into latching position with the latch bolt 23, the bolt 26 has a lug 35 extending over a lug 36 projecting from bolt 30, so that the lug 35 in contacting with the lug 36 during the downward movement of the bolt 45 23, will move the bolt 30 downwardly also, whereby both bolts simultaneously enter the recesses or keepers 32.

In operation, when the doors 4 and 5 are closed, the door 4 being closed first, so that 50 the door 5 can be closed without interfering with the bar 18 and lug 35 which project beyond the edge of the door 4, the lever 6 in being swung will manually move the hook 9 into the keeper 10 and the bolt 23 downwardly into its keeper. The movement of 55 the lever 6 will slide the bar 18, whereby the lever 12 is simultaneously swung with the lever 6, to move the hook 15 into the keeper 16, and the bolt 30 is also depressed with the bolt 23, in order that all four latch 60 members for the upper and lower corners of the two doors are simultaneously moved to latching position. Furthermore, the hooks 9 and 15 in swinging into their keepers, will 65 slightly raise the free edges of the doors

and support the doors against sagging under the weight thereof, and relieving the hinges of the doors from strain. The upper latches thus serve as means for hanging the doors, as well as latching same. When the lever 70 6 is swung to disengage the hook 9 from the keeper 10, the bar 18 being retracted, enables the spring 17 to swing the lever 12 to remove the hook 15 from the keeper 16, and the bolt 23 in being raised, enables the 75 spring 33 to raise the bolt 30 also, so that all four latch members are simultaneously disengaged from their keepers.

The door 5 can then be opened, inasmuch as the lever 12 can readily move from over 80 the bar 8, while the lugs 36 can move from under the lug 35. The door 4 can then be opened after the door 5 has been moved open.

If entrance must be had through the doors, for unlatching them and for exit after latching the doors, no other door being available for this purpose, then, an auxiliary or secondary door can be provided in the door 5, by sawing or cutting the door 5 along the dotted line 37, thereby providing an auxiliary or secondary door through which a person can pass when the doors are latched, and in this event, the latch bolt 30 and its parts are eliminated, and the secondary door is locked in any ordinary manner (not 95 shown).

Having thus described the invention, what is claimed as new is:—

1. A latching device for double doors comprising latches for the two doors at the 100 upper and lower ends of both doors, one of the latches being manually operable, and means for operating the other latches from the manually operable latch including co-operable portions between the latches of the 105 two doors, so that all of the latches are simultaneously moved with the manually operable latch.

2. A latching device for double doors, comprising latches for the two doors at the 110 upper and lower ends of both doors arranged in pairs, the latches of one door being manually operable, the latches of the other door having spring means for moving them to releasing position, and 115 means between the latches of the upper and lower pairs for moving the second named latches to latching position with the manually operable latches.

3. A latching device for double doors, 120 comprising slideable latch bolts for the two doors, one of which is manually operable, and lugs carried by said bolts to contact when the doors are closed for sliding the other bolt with the manually operable bolt. 125

4. A latching device for double doors comprising a pair of latch bolts for the two doors, guides for said latch bolts, one latch bolt being manually operable, spring means for the other latch bolt to move it to releas- 130

- ing position, and lugs cooperable when the doors are closed carried by two bolts for sliding the second named bolt to latching position with the manually operable bolt.
5. A latching device for double doors comprising two swinging latches, each of which is adapted to be carried by one of the doors for holding such door closed, one of the latches being manually operable to swing it to and from latching position, and portions movable with said latches and adapted to move into engagement when the doors are closed for operatively connecting the latches so that the other latch is swung to and from latching position with the manually operable latch.
6. A latching device for double doors, comprising a pair of swinging latches for the two doors, one of which is manually operable, spring means for swinging the other latch to releasing position, and a slidable bar connected to one latch, said bar and other latch having cooperable portions whereby the second named latch is moved to latching position with the manually operable latch.
7. A latching device for double doors,
- comprising a pair of latch levers for the two doors, means for fulcruming said levers, one of said levers having a handle, spring means for moving the other lever to releasing position, a slideable bar movable with the first named lever, the second named lever and bar having portions to engage one another for moving the second named lever to latching position with the first named lever.
8. A latching device for a double door, comprising a pair of latch levers having hooks at their upper ends to engage keepers carried by the lintel of the door frame for latching and hanging the doors, means for fulcruming said levers to the two doors, one lever having a handle, and means adapted to engage when the doors are closed for swinging the other lever with the lever having the handle when the doors are closed.

In testimony whereof I have signed my name to this specification in the presence of two subscribing witnesses.

WILLIAM A. STEFFEN.
